UNITED STATES PATENT OFFICE.

CORNELL FLAGSTAD, OF MINNEAPOLIS, MINNESOTA.

COLLAPSIBLE CARRIER.

Application filed April 3, 1924. Serial No. 703,971.

This invention relates to collapsible carriers of the general type shown in my application for patent Serial Number 677,175, filed on November 26th, 1923, of which the present application is a continuation in part, and the main object is to provide a novel, efficient and practical crate or box, in which the side and end sections are hinged together at their adjacent ends, and in which the closures or heads for the open ends, or top and bottom, are releasably secured, so that they may be readily removed when the crate or container is to be collapsed or folded together, as when it is to be returned to an original shipper. More specific objects are to provide a particularly novel construction of removable sections, herein termed "heads", and a particular type of hinge construction which is peculiarly adapted for connecting the side and end sections together. As the opposite open ends of the crate and the corresponding "heads" for closing the same are preferably identical in construction, only one of said crate ends and heads are herein illustrated.

The invention is fully illustrated by the views of the accompanying drawings, and will be readily understood therefrom when examined in the light of the following specification and claims, in which reference will be made to the various figures and elements shown, by reference characters, like reference characters referring to corresponding elements in the various views shown.

Fig. 1 is a top or plan elevation of the crate embodying the invention.

Fig. 2 is an enlarged sectional detail view on the line 2-2 in Fig. 1.

Fig. 3 is a side elevation of the upper end of the crate, as seen when looking up against Fig. 1.

Fig. 4 is an enlarged detail view on the section line 4-4 in Fig. 1.

Fig. 5 is a horizontal plan view of the preferred hinge construction, as on the line 5-5 in Fig. 4.

Fig. 6 is a fractional detail section on the line 6-6 in Fig. 5.

Fig. 7 is a perspective detail showing a modification of our improved hinge.

The head of the crate is designated broadly by the character A, the end sections by the character B, the side sections by the letter C, and the corner hinges by the letter D.

The end sections B of the crate consist of frames including vertical slats 8 secured to-

gether by suitable cross slats 9; and the other or side sections C comprise vertical slats 10 which are connected by horizontal adjoining end slats 11 and 12. One of the slats 11 or 12 (11 in the present instance) is provided with notches 13, between the vertical members 10, to receive the securing bolts 14 and 15 of the head A. This construction 11-12, is superior to a single board with the openings 13 mortised out of it, as such requires a more expensive and slower operation to complete, and is also believed to be superior to a construction having two straight slats spaced apart so as to complete the necessary openings with the vertical slats, as such an arrangement leaves the upper slat, as 12, which is necessarily quite narrow, without the bracing of the adjacent slat against its under edge.

The cover section or head A is a single frame of rigidly connected slats 16, 17, 18, 19 and 20. The slats 16, 17 and 18 project beyond the outer slats 20 so as to slidably rest upon the upper edges of the end frames B, which edges are lower than the edges of the sections C. The slats 20 are comparatively short, while the slats 19 project beyond the slats 16, 18, as the securing bolts 14 and 15, hereinbefore mentioned.

The slat 16 is spaced inwardly from the adjacent side section C, and the resulting intermediate space is normally closed or filled in by a locking member 21, which is rigidly secured to the slat 16, as at 22, and is normally spring held down against the bolts 14, by suitable springs 23.

Now when the crate is to be set up and the four vertical sections have been arranged in a quadrangular fashion, the cover or head A is placed thereupon, the locking strip 21 is raised high enough so that the bolts 14 can be fully inserted in their openings 13. The bolts 15, which are considerably shorter than the bolts 14, will now drop in line with their corresponding openings or notches 13, and the head is slid in that direction until the slat 18 meets the adjacent section C, at which time the locking member 21 will be released, and as it drops back to the position indicated in Figs. 1 and 4, it will securely lock the head in place

and in such a manner that the head will be braced rigidly between the opposite side sections. To remove the head it is merely necessary to lift the member 21, pull the head in that direction, raise the opposite

edge of the head, and then move the head in the reverse direction, and thus releasing the bolts 14.

At the upper edges of the side sections C, 5 I provide bridging members E and F, which are designed to increase or extend the bearing for the cover bolts which pass thereunder, and are arranged preferably between the ends of the sections, where they are most 10 apt to bulge or spread away from the head, and thus these members effectively decrease if not eliminate accidental displacement of the cover locking bolts. The member E consists of an inwardly bowed iron strap, the 15 ends of which are secured to the adjacent vertical slats 10. The locking member 21 may be grooved out, as indicated in Fig 1, so as not to interfere with the bridge E.

The bridge F, shown in Figs. 1 and 2, 20 is nailed flush onto the vertical crate slats 10, and is provided with reinforcing flanges 24 and 25, and an upwardly inclined flange 26. Thus, if the head is a little large for its opening, even when contracted toward the 25 opposite side, and the cover rests upon the flange 26, it need only to be pushed or pressed down, and this action will automatically spread the side section away until the cover slips down into place.

30 The hinges D which are clearly illustrated, and have some modifications, as indicated in Figs. 1, 3, 4, 5, 6 and 7, each consists of a pair of novel strap iron members pivotally connected by a pintle. The hinge members may be identical in construction or one or both may be substituted by modified members. The specific construction of the hinge members and the method by which they are secured is of vital consequence and importance, especially as considered in the art of 35 crate making, and will now be set forth in detail, attention being directed particularly to Figs. 5, 6 and 7.

The hinge members will hereinafter be 40 termed "butts", and three designs 27, 28 and 29 are indicated, although they all have certain features in common; and the same statement is true of the pintles 30 and 31.

45 The butts are all substantially U-shaped so that they may be secured against both the outer and inner sides of the crate sections, and are all provided or formed with loops 32 which serve as bearings for the pintles. These bearings are punched or bent 50 out integrally from the adjacent or inner corners of the butts, and are formed at angles of approximately forty-five degrees (see Fig. 5) to the sections on which the butts are secured, so that their centers will 55 be offset, as shown. Thus when the sections B and C are folded together sufficient space will be allowed between the inner 60 butt plates to freely accommodate the heads of the securing nails, and at the two corners 65 of the crate where the sections B and C are

swung into the same plane there will be enough room between the end portions of the butts to accommodate the bent over ends of the pintles. The pintles may consist of ordinary rivets, as is frequently the case, but 70 rivets have several disadvantages in this construction and are not as efficient as the pintles 30, 31 which I have shown. Thus, as the bearing loops 32 are only pressed into shape they would easily spread from the 75 riveting blows, and even if the rivets could be completed without distorting the bearings, there is always the possibility that an excessive strain on the crate will partly open the bearings and may even pull the 80 adjacent end portion of the butt away from the end of the crate. In that event the rivet might slip through the narrow of the bearing to the wood, and unless the rivet has an unusually large head it might even fall 85 out of the hinge entirely and be lost. To overcome these difficulties I provide the pintles 30 and 31. The pintle 30 is a nail, the head of which is obviously a good deal larger than the head of an ordinary rivet of the 90 same size, and would not fall through the bearings under any ordinary circumstances. The opposite end of the nail is bent back upon the outer periphery of the bearing and engages thereagainst, so as to clamp the 95 nail in place and prevent it from slipping through the neck of the bearing should it open, as above mentioned. It will also be noted, especially in Fig. 5, that the bent end of the nail pintle is to the outside of the 100 crate so that it cannot mark or mar any of the articles shipped in the crate. In the modification shown in Fig. 7 both ends of the wire pintle 31 are bent about the bearing, thus further emphasizing and adding 105 to the advantages of the bent nail pintle.

The hinge butts are nailed to their respective crate sections, but the nail holes in the butts are so arranged that a distinct advantage, in firmly securing the butts to the 110 wood, results. Thus, when the butt 27 is in place upon the crate section, the first nails 33 are driven from the outside in and clinched over against the inner plate, a steel block or some other object being held 115 against the plate to prevent the end thereof from being bent out. The nails 34 are then driven from the inner side, and as they strike the outer plate at points intermediate the nails 33 they will not only clinch against 120 the outer plate (as shown) but will also tend to slightly bulge the outer plate between the heads of 33, and by so doing will obviously increase the tension between the outer plate and the heads of the nails 33, 125 and make them more rigid and firm in the wood.

The hinge butts 28 and 29 are shown with their inner plates 29^a considerably longer than their outer plates 29^b, the object being 130

to proportion the sizes of these plates to the relative strains to which they are put, and thus economize on the material used in the hinges. Thus, as the vertical sections of the 5 crate are pulled or forced outwardly the normal strain to the hinge will be effective substantially through the forty-five degree line shown in Fig. 5. This being true the strains will obviously be equal on both plates 10 29^a and 29^b, but the strain on the plate 29^a is directly taken up by only the nails driven through it, but the plate 29^b is bent at right angles thus forming a hook, as 35, which 15 pulls directly upon the section, and thus eliminates the strain on the nail of the shorter plate to a great extent.

Having now fully shown and described my invention what I claim to be new and desire to protect by United States Letters

20 Patent is:

1. The combination in a crate having a detachable head adapted to be slidably secured thereon, of a locking member hingedly arranged on the crate near one edge of the 25 head, and spring means for normally holding said locking member in a locking position between a part of the head and the adjacent wall of the crate.

2. The combination of a crate having a 30 head adapted to be secured thereon by a forth and back movement thereof, a spring retained locking member adapted to yieldingly lock the head in its closed position, and hinges for movably securing the locking 35 member in place.

3. The combination with a crate, of a head therefore having retaining members at 40 opposite edges thereof adapted to be engaged into opposite sides of the crate by sliding movements of the head, a locking member adjacent to the retaining members at one side of the crate for preventing sliding of the head, so as to lock it to the crate, and means for hingedly securing the locking 45 member to the head.

4. In a crate having end sections and side 50 sections, the upper edges of the end sections

being lower than the upper edges of the side sections, a head adapted to be supported at its ends upon the said upper edges of the end 55 sections, oppositely extending securing members projecting from the side of the head for sliding engagement with the side sections, the securing members at one side of the head being longer than the securing 60 members at the opposite side, and means for releasably locking the head to the crate consisting of a transverse strip hingedly secured to the head.

5. The combination with the side and end 65 sections of a crate, of a head comprising longitudinally extending members and transverse members, said transverse members projecting beyond the longitudinal members for sliding engagement with the 70 side sections of the crate, and a hingedly mounted locking member independent of said head members for engagement with one of the side sections to lock the head between said side sections.

6. The combination with side and end sections of a crate, of a head comprising longitudinal members and transverse members, said transverse members continuing in rigid 75 extensions beyond the outer longitudinal members for sliding engagement with opposite sections of the crate, and a locking member hingedly secured upon one of said outer longitudinal members for engagement against the adjacent section of the crate. 80

7. A crate having a detachable cover provided with a rigidly projecting bolt adapted to engage one of the side walls of the crate, a bridging member secured upon the inner 85 side of said side wall so as to frictionally receive the cover bolt, said bridging member having an inwardly sloping flange for engagement by the bolt so that the side section will be sprung outwardly when the rigid bolt of the cover is pressed down 90 against the bridging member.

In testimony whereof, I affix my signature.

CORNELL FLAGSTAD.
